CARRIER ROD OPERATING MECHANISM
FOR FLAT KNITTING MACHINESAlbert Friedmann, Wyomissing, Pa., assignor to
Louis Hirsch Textile Machines, Inc., New York,
N. Y., a corporation of New York

Application June 26, 1934, Serial No. 732,455

8 Claims. (Cl. 66—127)

This application is a continuation, in part, of application Serial No. 709,730, filed by this inventor, Albert Friedmann, on February 5, 1934.

The invention hereof relates to flat knitting machines, particularly those for the manufacture of full fashioned hosiery, and specifically to the mechanisms for driving and controlling the carrier rods. By means of it a single friction device on the friction rod may be utilized to operate a multiplicity of carrier rods in any sequence or in any combination desired, or a multiplicity of similar devices on the friction rod may be employed, each of them being used to control any one of the friction rods in any desired sequence. The same device, or devices, is also utilized to establish each carrier rod in its correct position against an end stop, or other stop, which determines its limit of travel before the beginning of each stroke. Thus the invention eliminates the serious and very common defect in present day flat knitting machines of displacement of carrier rods as the result of the shock which occurs when one of them strikes its stop.

The invention also includes means for securely holding idle carrier rods against their end stops during the operation of another rod. Another common difficulty is thereby eliminated, namely, the displacement of an idle carrier rod through contact of its thread carrier with the thread carrier of an operating carrier rod at the beginning of a stroke. Some present day machines are provided with latches intended to accomplish this latter object but their method of operation is such that all of the rods are simultaneously released, with the result that some of them may be displaced through interference of the thread carriers at the beginning of the stroke of one of the rods in spite of the latches. Furthermore, such latches are operated by means other than the carrier rods themselves which injects into the extremely complicated mechanism of the flat knitting machine another delicate problem of timing. The carrier rod latching device of this application, although carried by the narrowing head in a manner substantially identical to that of the old type latches, is operated by the carrier rods themselves entirely independently of the rest of the machine and in such a way that each rod at the end of a stroke is automatically locked and automatically unlocks the carrier rod which makes the next thread laying stroke.

By this invention, therefore, each rod is not only moved into correct position for the beginning of its stroke and locked in that position but also it is unlocked by the carrier rods which perform the next preceding stroke so that no possible difficulty can arise in the timing of these operations.

A further feature of the invention which is of great practical value, is that its application involves no changes in the standard knitting machine beyond replacing the standard friction devices with the special selective carrier rod operating device or devices of this invention, substituting for the ordinary carrier rod locking latches the special latches of this invention, and equipping the standard carrier rods with the special drive blocks and latch operating blocks of this invention. In short, the invention may be applied to a standard knitting machine without substantial alteration of any of its standard parts.

The invention may be utilized for a majority of the types of knitting of which a standard knitting machine is capable, but it is particularly useful in the knitting of the so-called ringless types of hosiery fabric in which different threads, usually three in number, are employed in succeeding courses, thus spreading any inequalities caused by variation in thread size over wider areas and, consequently, reducing or eliminating the ring-like effect caused by such inequalities when they appear in adjacent courses.

The invention may be readily applied to such knitting machines as that disclosed and described in application Serial No. 701,737 filed December 11, 1933, by Albert Friedmann for the knitting of the special type of ringless stocking having a re-enforced selvage which, together with the method of making it, is also disclosed in that application.

For the purposes of this application the device as shown is applied to three carrier rods and their operation will be described as they are used in the making of a simple three thread ringless fabric. It will be understood, however, that this limited description implies no equivalent limitation in the scope of the invention.

In the drawings:

Figure 1 is a plan view of three carrier rods of a flat knitting machine, and the means by which they are operated and controlled;

Fig. 2 is a sectional end elevation on the line 2—2 of Fig. 1 of the device which automatically selects and operates the carrier rods through the reciprocation of the friction rod and which also assures the proper positioning of each carrier rod at the beginning of its stroke;

Fig. 3 is a diagrammatic view of the carrier rod latches at the respective ends of the machine in the positions assumed by them when the carrier rods are disposed as shown in Fig. 1;

Fig. 4 is a similar diagrammatic view of the position of the same latches after the lowest rod shown in Fig. 1 has completed its stroke to the left;

Fig. 5 is a similar diagrammatic view of the latches showing their position when the upper

rod shown in Fig. 1 has completed a stroke to the right;

Fig. 6 is a view of one form of a carrier rod driving block; and

5 Figs. 7 and 8 are similar views of another type of carrier rod driving block also showing the driving finger in two different driving positions.

Three carrier rods 1, 2 and 3 are shown in Fig. 1. With the exception of the special driving blocks 10 and latch blocks with which they are equipped and which will be described hereinafter, these rods may be standard in all respects. Corresponding end stops 4, 5 and 6 are also shown in Fig. 1 mounted in the usual manner on narrowing head 15 1 at the left end of the machine. At the other end 15 of the machine similar end stops 8, 9 and 10 are similarly mounted on narrowing head 11. These stops determine the extreme limits of travel of the carrier rods in the well known manner.

20 In Fig. 1 is also shown the standard reciprocable friction rod 12 upon which is mounted a friction box 13 provided with the usual frictional devices. Upon friction box 12 are pivotally mounted fingers 14, 15 and 16, the respective lengths of 25 which are such that their ends overlie carrier rods 1, 2 and 3. All three fingers are mounted on a common shaft 17 in such a way that they may be individually rocked in a vertical plane.

These fingers also extend rearwardly from their 30 pivots as arms 18, 19 and 20 which terminate substantially beneath cross bar 21 of frame 22, which is also mounted upon or is an integral part of friction box 13. The sides of frame 22^a are extended downwardly to form supports for a bearing 23 slidably surrounding a shaft 24 so that frame 22, although it can slide longitudinally, is rigidly braced against other movement insuring that the various parts of the device will be maintained in correct position with respect to the carrier rods. Each of the arms 18, 19 and 20 is connected to cross bar 21 of frame 22 by means of a spring 25. Thus normally the fingers will be maintained in "down" position with their ends slightly above their respective rods. Rocking of 40 fingers 14, 15 and 16 is automatically effected by cams 26, 27 and 28 respectively, mounted on a changing shaft 29 which is rotatably mounted in suitable bearings so that it overlies the rear end of arms 18, 19 and 20. Each of the cams 26, 27 and 28 is slidably mounted upon changing shaft 29, the hub of each being provided with one or more splines 30 which engage with corresponding 45 spline slots 31 in changing shaft 29. Thus although cams 26, 27 and 28 are slidable upon changing shaft 29 any rotation of shaft 29 will impart a corresponding rotation to the cams. Cams 26, 27 and 28 are mounted in proper position with respect to each other and to the arms 18, 19 and 20 by any suitable means and engage 50 with those arms through the medium of a roller 32 on each arm. Thus when friction box 13 is reciprocated by friction rod 12 not only the fingers 14, 15 and 16 and arms 18, 19 and 20 but also rollers 32 and cams 26, 27 and 28 will reciprocate as a unit, the cams sliding along shaft 24 and maintaining their operative alignment with the arms. Each of cams 26, 27 and 28 is so shaped and its working surface so distributed about the shaft that the finger which it controls 55 will be maintained in its raised and lowered positions at appropriate times during the knitting operation by suitable rotation of shaft 29.

Shaft 29 may be rotated by any suitable mechanism which will impart proper timing to the cams. 70 The mechanism shown in Fig. 1 for rotating shaft

29 consists of a cam 35 upon the main cam shaft 36 which operates a rock lever 37 through roller 38. Lever 37 in turn rotates shaft 29 in a step by step manner through a pawl 39 and ratchet wheel 40. This form of drive is well known to those skilled in the art and can be designed by them to impart the required speed of rotation to shaft 29 to harmonize its action with the knitting cycle.

The purpose of fingers 14, 15 and 16 is to translate the reciprocation of friction rod 12 to carrier rods 1, 2 and 3 in accordance with the requirements of the knitting operation being performed. To make this possible carrier rods 1, 2 and 3 are provided with driving blocks 41, 42 and 43 respectively, so positioned on each rod as to be engageable with the corresponding finger 14, 15 or 16 at either end of each stroke and at any intermediate point. In one form of the device each of the driving blocks 41, 42 and 43 is of the form 20 best shown in Fig. 6 and consists of a metallic block attached to and projecting above the carrier rod and provided with sloping surfaces 44 and 45 leading up to a centrally positioned rectangular depression 46 of suitable size to receive 25 the end of a finger.

It will be apparent that whenever during the reciprocation of the friction rod one of the fingers 14, 15 or 16 is engaged in a corresponding recess 46 of its drive block the carrier rod will 30 also be reciprocated either to the right or left.

In the knitting of simple three thread ringless fabric which, as already stated, had been chosen for illustration herein, the device described above 35 operates as follows:

It will be assumed that carrier rods 1, 2 and 3 operate in that sequence to lay the three threads required. With the rods in the position shown in Fig. 1, viz: rod 1 to the left, and rods 2 and 3 to the right, the first rod to be reciprocated will 40 be rod 3 to lay a thread from right to left, and to prepare carrier rod 1 for operation on the return stroke. It will also be assumed that friction rod 12 is also at the right end of its reciprocatory path ready to move to the left. Shaft 29 has been 45 rotated so that cam 28 has permitted finger 16 to pass into the recess in drive block 43. Finger 14 is also in down position but finger 15 is "up". When friction rod 12 is driven to the left rod 3 will be carried along until it strikes end stop 6, 50 whereupon friction rod 12 will continue on to the end of its stroke, the friction box 13 remaining stationary. Thereupon, before the beginning of the return stroke to the right, shaft 29 will be rotated again so that cam 28 will lift finger 16 55 out of engagement with drive block 43, releasing carrier rod 3 from its driving connections. As the end of this stroke is approached finger 14 will strike the sloping surface 44 of drive block 41 on carrier rod 1, and will fall into depression 60 46. In case rod 1 has been jarred out of its position against end stop 4, finger 14 will move it back against the end stop as the stroke of rod 3 is completed. Thereupon, shaft 29 will be rotated again 65 so that the cams will lift finger 16 out of engagement with drive block 43 on carrier rod 3 and will permit finger 15 to drop into its "down" position ready to engage drive block 42 at the end of the next stroke.

Rod 1 is now coupled to finger 14 and ready to 70 be driven from left to right by the next movement of the friction rod 12. Towards the end of this stroke of rod 1 finger 15 will strike and ride up on the sloping surface of drive block 42 on carrier rod 2 as already described in connection 75

with rod 1, and at the end of this stroke will fall into the recess of drive block 42. Then finger 14 is raised into its "up" position by cam 26 to free carrier rod 1, and rod 2 is ready to be driven from right to left to lay the next thread. Finger 16 is also lowered at this time into position to engage drive block 43 on carrier rod 3 at the end of this stroke. As already described, in connection with the operation of carrier rod 1, if carrier rod 2 happens to have been jarred or otherwise moved from contact with end stop 9, it will have been moved back into its correct position at the initial engagement of finger 15 with the recess in drive block 42 at the end of the stroke of carrier rod 1. In this manner the carrier rods are not only driven in the desired sequence by one or another of the fingers 14, 15 and 16, but the proper positioning of each rod just before it begins its operating stroke is assured by the engagement of its finger at the end of the stroke of the immediately preceding working carrier rod.

In view of the fact that the several thread carriers closely overlie each other between carrier rod strokes and that very slight sagging or bending will cause them to rub, it has happened frequently that the thread carrier of an idle rod is moved into the operating field of the sinkers by the thread carrier of the working carrier rod with consequent damage to the sinkers and needles.

To prevent this the device of this invention includes means for locking the idle rods against their end stops during the greater part of the reciprocation of the working carrier rod. This device, in the form shown herein, consists of a set of pivoted latch levers 47, 48 and 49 carried by a shaft 50 on narrowing head 7 and an opposing set of latch levers 51, 52 and 53 carried by a shaft 54 on narrowing head 11. These levers are provided with latches 55, 56 and 57, and 58, 59 and 60 respectively, the three latches of each set lying directly above the path of travel of carrier rods 1, 2 and 3 in the order indicated.

The latch levers on their free ends are provided with downwardly depending shoes 61, 62, 63, 64, 65 and 66, respectively. Shoe 61 overlies the path of carrier rod 3; shoe 62 overlies the path of carrier rod 1; and shoe 63 overlies the path of carrier rod 2, latch levers 47, 48 and 49 being suitably formed to make this possible, as shown in Fig. 1. Similarly the other set of opposing latch levers is provided with similar shoes 64, 65 and 66 lying above the paths of carrier rods 3, 1 and 2 respectively. That is to say, there is a pair of opposed but otherwise identical latch levers for each rod on each narrowing head. Each is independently rockable upon its shaft, the free ends being urged downwardly by springs 67 attached to any suitable anchorage.

As generally stated heretofore these latches serve to lock the idle carrier rods against their end stops to guard against displacement through interference of thread carriers. To effect this result each carrier rod is provided with two opposed but otherwise identical combination shoe lifter and latch plate blocks so positioned adjacent the ends of each carrier rod that the respective latches will engage with them when the rods have reached the ends of their travel. The combination blocks for carrier rod 1 are shown at 68 and 71, those for carrier rod 2 at 69 and 72, and those for carrier rod 3 at 70 and 73. Each block is provided with an inclined surface 74, a latch notch 75 and a shoe support 76, and projects above the carrier rod sufficiently so that it

will strike the shoe lying in its path and raise it sufficiently to disengage the latch on the same latch lever as the shoe, from the latch notch on the carrier rod with which the latch is associated.

This will be made clearer in the following description of the operation of the latches. To avoid confusion it must be remembered that the latches are operated by the carrier rod themselves. In consequence, since the rods have been assumed to function in 1, 2, 3 order carrier rod 3 must be used to release the latches of carrier rod 1; carrier rod 1 releases the latches of carrier rod 2; and carrier rod 2 releases the latches of carrier rod 3. Hence the shoes 61 and 64 of latch levers 47 and 51 as already stated, are positioned so as to be lifted by block 70 or 73 to unlock rod 1; the shoes 62 and 65 of latch levers 48 and 52 are positioned so as to be lifted by block 68 or 71 on carrier rod 1; and shoes 63 and 66 on latch levers 49 and 53 are positioned so as to be lifted by blocks 69 and 72 on carrier rod 2.

A series of carrier rod movements is illustrated by Figs. 3, 4 and 5. In Fig. 3 the carrier rods are shown in the same position as in Fig. 1 and the same assumption applies, viz: that carrier rod 3 is to be the first to be operated. This rod is free to move, its latch 60 being disengaged from block 73 as the result of the lifting of shoe 66 on the same latch lever 53 by block 72 on carrier rod 2, as shown in dotted lines, when this carrier rod last reached the position shown in Fig. 3 at the limit of its travel to the right.

Rod 1 is locked up because block 70 on rod 3 does not engage shoe 61 on latch lever 47, as shown in dotted lines, hence latch 55 on that lever is free to engage with the latch notch of block 68 on carrier rod 1. Rod 2 is also locked up by latch 59 for a similar reason, viz: shoe 65 is not in engagement with block 71 on carrier rod 1, as shown in dotted lines. Therefore, when carrier rod 3 is drawn from right to left it will be impossible for either rod 1 or rod 2 to move.

Fig. 4 illustrates diagrammatically the situation created by the arrival of carrier rod 3 at the end of its stroke to the left. Latch 57 has engaged with the latch notch of block 70 on rod 3 because the position of rod 2 at the right remains unchanged, and block 69 on rod 2 consequently remains disengaged from shoe 63, as shown in dotted lines. Since the operation of the latch 59 of rod 2 is under the control of rod 1, which has not changed its position, rod 2 remains locked up as before. Rod 1, however, has been unlocked through the lifting of shoe 61 of latch lever 47 by block 70 on rod 3 at the end of the right to left stroke of rod 3. Therefore, rod 1 can now be driven from left to right to perform the next thread laying stroke.

It will be noted that the two idle rods are locked up whereas the next working rod is now unlocked.

Fig. 5 diagrammatically illustrates the condition which exists after rod 1 has completed its stroke from left to right. Latch 58 has dropped into the latch notch of block 71 locking up rod 1 since block 73 on rod 3 is out of engagement with shoe 64, as shown in dotted lines. The arrival of rod 1 at the right end of its stroke has caused block 71 to lift shoe 65 on latch lever 52, as shown in dotted lines, with the result that rod 2 has been unlocked by the lifting of latch 59 out of the clutch notch of block 72. Since rod 2 still remains in its original position at the right rod 3 remains locked up through the continued disengagement of shoe 63 of latch lever 49 from 75

block 69 on rod 2, as shown in dotted lines. Here again, the two idle rods are locked up and the rod next to work unlocked.

For the laying of the next thread rod 2 will be driven from right to left. When this stroke is completed it will be locked up as the result of the engagement of latch 56 with the latch notch of block 69, this being no longer prevented by the engagement of block 68 on rod 1 with shoe 62 on latch lever 48. Rod 1 will remain locked because rod 3 has not changed its position but rod 3 will be unlocked as the result of shoe 63 being lifted by block 69 on rod 2, and thus made ready for its next working stroke. As in the other instance 15 previously described, the two idle rods are locked up and the next working rod is unlocked automatically and solely through the operation of the carrier rods themselves.

If the carrier rods are operated in some other sequence than that described the cams on changing shaft 29 will, of course, be shaped to effect the necessary operation of the driving fingers and the latch levers will also be so modified that the carrier rod next to operate will be unlocked by 25 the rod in operation during the preceding stroke.

A modification of the invention is described in Figs. 7 and 8. In this the drive block with which each carrier rod is provided is modified by bevelling outwardly the upper corners of the 30 side walls of recess 46 as shown at 77 and 78, and bevelling the lower edges of the fingers 14, 15 and 16 to correspond as shown at 79 and 80. Also the relation between the fingers and the driving blocks is such that each finger when in "down" 35 position as shown in Fig. 7 will be fully seated in a drive block recess 46, but when in "up" position will not clear the drive block entirely as in the form originally described and disclosed in Fig. 6 but will still remain within recess 46 sufficiently to allow the bevelled edge of the finger 40 to engage with the bevelled edge of the drive block as shown in Fig. 8. With this arrangement the knitting operation may be performed as heretofore described in so far as the up and down 45 manipulation and sequence of the fingers is concerned, the only difference being that when in "up" position each finger will still engage with its corresponding carrier rod drive block to the extent shown in Fig. 8. However, since the idle rods 50 are locked up by the latches heretofore described this engagement is immaterial because the fingers so engaged will readily snap out of the recesses as soon as they begin to move upon a friction rod stroke.

55 While this modified arrangement is of no particular advantage for knitting such as that heretofore described, in which the carrier rods are successively driven the full width of the fabric, it is extremely useful in any knitting in which 60 the travel of any of the carrier rods is less than that of others since the rods may be driven by the fingers when in the raised position shown in Fig. 8. For such a purpose spring 25 which urges each finger downwardly must be of sufficient 65 strength to retain the bevelled edge 79 or 80 of the finger against the adjacent bevelled edge of the carrier rod drive block during the driving of the rod. Under this condition a rod can be driven in this way and yet may be stopped at any intermediate point without preventing the friction 70 box and the fingers from proceeding onward to the end of their stroke, since the finger will automatically release itself from the carrier rod in question. Of course, the frictional engagement 75 of friction box 13 with friction rod 12 must be

sufficient to prevent displacement of the friction box upon the friction rod when this snapping out action occurs. Thus it becomes possible to drive two rods over different distances simultaneously one, for example, entirely across the 5 fabric by means of a finger fully seated in recess 46 as shown in Fig. 7, and the other a shorter distance by means of a finger engaged as shown in Fig. 8, both operations being performed by a single friction device traveling with the friction rod over 10 the full width of the fabric.

What I claim is:

1. In a flat knitting machine provided with a reciprocable friction rod and carrier rods, carrier rod driving mechanism comprising a friction 15 device frictionally engaged with said friction rod, a plurality of adjustable carrier-rod driving means carried by said friction device each of which is engageable with a different carrier rod, means for maintaining two of said carrier rod 20 driving means in adjustment to engage their respective carrier rods during each traverse of the friction rod, a drive block upon each carrier rod provided with a recess with which its respective driving means can engage to drive said carrier 25 rod in either direction, said driving block also being provided with means for guiding any of said driving means which is disengaged from but in engageable adjustment with its carrier rod upward to the top of said block from which it can pass automatically into said recess whenever said driving means assumes a position above said recess.

2. In a flat knitting machine provided with a reciprocable friction rod and carrier rods, carrier 35 rod driving mechanism comprising a friction device frictionally engaged with said friction rod, a plurality of adjustable carrier-rod driving means carried by said friction device each of which is engageable with a different carrier rod, means 40 for maintaining a plurality of said carrier rod driving means in adjustment to engage their respective carrier rods during each traverse of the friction rod, a drive block upon each carrier rod provided with a recess with which its respective 45 driving means can engage to drive said carrier rod in either direction, said driving block also being provided with means for guiding any of said driving means which is disengaged from but in engageable adjustment with its carrier rod upward to the top of said block from which it can pass automatically into said recess whenever said driving means assumes a position above said recess, and means for maintaining the remaining carrier rod driving means in non-engageable adjustment.

3. In a flat knitting machine provided with a reciprocable friction rod and carrier rods, carrier rod driving mechanism comprising a friction device frictionally engaged with said friction rod, a plurality of adjustable carrier-rod driving fingers carried by said friction device each of which is engageable with a different carrier rod, means for maintaining two of said carrier rod driving fingers in adjustment to engage their respective carrier rods during each traverse of the friction rod, a drive block upon each carrier rod provided with a recess with which its respective driving finger can engage to drive said carrier rod in either direction, said driving block 70 also being provided with means for guiding any of said driving fingers which is disengaged from but in engageable adjustment with its carrier rod upward to the top of said block from which it can pass automatically into said recess when-

ever said driving finger assumes a position above said recess.

4. In a flat knitting machine provided with a reciprocable friction rod and carrier rods, carrier rod driving mechanism comprising a friction device frictionally engaged with said friction rod, a plurality of adjustable carrier-rod driving fingers carried by said friction device each of which is engageable with a different carrier rod, means for maintaining a plurality of said carrier rod driving fingers in adjustment to engage their respective carrier rods during each traverse of the friction rod, a drive block upon each carrier rod provided with a recess with which its respective driving finger can engage to drive said carrier rod in either direction, said driving block also being provided with means for guiding any of said driving fingers which is disengageable from but in engageable adjustment with its carrier rod upward to the top of said block from which it can pass automatically into said recess whenever said driving finger assumes a position above said recess.

5. In a flat knitting machine provided with a reciprocable friction rod and carrier rods, a carrier rod driving mechanism comprising a friction device frictionally engaged with said friction rod, a plurality of carrier rod driving fingers rockably mounted on said friction device, each of which is engageable with a different carrier rod, resilient means for maintaining all of said fingers normally in position to be engageable, each with a driving block upon its respective carrier rod, means for moving one finger out of engageable position between successive traverses of the friction rod, each of said driving blocks being provided with a recess with which its respective driving means can engage to drive said carrier rod in either direction, and means for guiding any of said driving fingers which is disengaged from but in engageable position with its carrier rod upward to the top of said block from which it can pass automatically into said recess whenever said driving means assumes a position above said recess.

6. In a flat knitting machine provided with a reciprocable friction rod and carrier rods, a carrier rod driving mechanism comprising a friction device frictionally engaged with said friction rod, a plurality of adjustable carrier rod driving fingers on said friction device, each of which is rockable into and out of engageable position with a different carrier rod, means for maintaining two of said carrier rod driving fingers in adjustment to engage their respective carrier rods during each traverse of the friction rod and the remainder of said carrier rod driving fingers in non-engageable adjustment, which includes a rotatable selector shaft, a multiplicity of selector cams rotatable with and slidable upon said selector shaft, one of which is engageable with each driving finger to rock into and out of carrier rod engageable position, means for rotating said selector shaft, a drive block upon each carrier rod provided with a recess with which its respective driving finger can engage to drive said carrier rod in either direction, and means for guiding any of said driving fingers which is disengaged from but in adjustable engagement with its carrier rod upward to the top of said block from which it can pass automatically into said

recess whenever said driving finger assumes a position above said recess.

7. In a flat knitting machine provided with a reciprocable friction rod and carrier rods, carrier rod driving mechanism comprising a friction device frictionally engaged with said friction rod, a plurality of adjustable carrier-rod driving means carried by said friction device each of which is engageable with a different carrier rod, means for maintaining two of said carrier rod driving means in adjustment to engage their respective carrier rods during each traverse of the friction rod, a drive block upon each carrier rod provided with a recess with which its respective driving means can engage to drive said carrier rod in either direction, said driving block also being provided with means for guiding any of said driving means which is disengaged from but in engageable adjustment with its carrier rod upward to the top of said block from which it can pass automatically into said recess whenever said driving means assumes a position above said recess in combination with means equal in number to said carrier rods each of which is adapted to lock against movement a different carrier rod when said rod is not in engagement with its driving means, the operation of said locking means being controlled by means on a carrier rod other than the one which it is adapted to lock.

8. In a flat knitting machine provided with a reciprocable friction rod and carrier rods, carrier rod driving mechanism comprising a friction device frictionally engaged with said friction rod, a plurality of adjustable carrier-rod driving means carried by said friction device each of which is engageable with a different carrier rod, means for maintaining two of said carrier rod driving means in adjustment to engage their respective carrier rods during each traverse of the friction rod, a drive block upon each carrier rod provided with a recess with which its respective driving means can engage to drive said carrier rod in either direction, said driving block also being provided with means for guiding any of said driving means which is disengaged from but in engageable adjustment with its carrier rod upward to the top of said block from which it can pass automatically into said recess whenever said driving means assumes a position above said recess, in combination with means equal in number to said carrier rods each of which is adapted to lock against movement a different carrier rod when said rod is not in engagement with its driving means, the operation of each of said locking means being controlled by means on a carrier rod other than the one which it is adapted to lock, each of said locking means comprising a pivoted lever provided with a latch engageable with a latch plate on its respective carrier rod at the end of the stroke of said carrier rod, and also being provided with a shoe engageable with a shoe lifter on another carrier rod, said shoe lifter being adapted to raise said lever by means of said shoe sufficiently to release its latch from the latch plate of the carrier rod which it locks immediately before said last-mentioned rod is required to move from its locked position.
